UNITED STATES PATENT OFFICE

JOSEPH A. McCARTHY, OF RICHMOND HILL, NEW YORK

FORCED DRAFT DEFLECTOR FOR GAS STOVES

Application filed February 25, 1930. Serial No. 431,187.

This invention relates to certain new and useful improvements in forced draft deflector for gas ranges.

The primary object of the invention is to provide a flue cap and deflector adapted for association with the outlet flue of a gas stove or range for receiving products of combustion escaping through the flue to direct them away from the walls of a room.

A further object of the invention is to provide a flue cap and deflector of the above type wherein the flue cap or deflector embodies a hood having an opening in its bottom wall in communication with the outlet flue of a gas range and having a further opening in the bottom wall for the ingress of air to increase the velocity of the products of combustion flowing through the flue cap and deflector to discharge the products of combustion with increased force and operating in a manner similar to a Bunsen burner, in which air is admitted to increase combustion.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a bottom plan view of the hood of the flue cap and deflector showing the bottom wall thereof provided with a relatively large flanged opening for association with the outlet flue of a gas stove or range and an elongated slot in the bottom wall at one side of the flanged opening for the admission of air at atmospheric pressure;

Figure 2 is a front elevational view of the flue cap and deflector showing the hood mounted upon the upper end of the collar that in turn is adapted for mounting upon the collar of an outlet flue;

Figure 3 is a vertical cross-sectional view taken on line 3—3 of Figure 2 showing the slotted opening in the bottom wall of the hood positioned rearwardly of the flue communicating opening in the bottom wall;

Figure 4 is a horizontal sectional view taken on line 4—4 of Figure 3;

Figure 5 is a front elevational view of the deflector equipped with a front grille, partly broken away and adapted for direct mounting on the stove flue in the absence of the upstanding collar.

55

Figure 6 is a front elevational view of another form of deflector hood, partly broken away and shown in section, illustrating the collar carrying the hood as mounted upon the outlet flue of the gas range with side or lateral openings in the bottom of the hood outwardly of the hood supporting collar;

60

Figure 7 is a vertical cross-sectional view taken on line 7—7 of Figure 6 showing the lateral opening in the bottom of the hood positioned rearwardly of the forward side of the collar and flue outlet; and

65

Figure 8 is a horizontal sectional view taken on line 8—8 of Figure 6 showing the laterally and rearwardly positioned openings in the bottom of the hood.

70

Referring more in detail to the accompanying drawings, there is illustrated a flue cap and deflector comprising a hood and a collar, it being understood that the hood may be directly mounted upon the outlet flue of a gas stove or range or mounted upon the upper end of a collar, the lower end of which may be attached to the outlet flue of the gas stove.

75

The hood comprises a bottom wall 5 of rectangular form as shown in Figures 1 and 4 with a relatively large opening 6 therein extending substantially the complete width of the bottom wall and surrounded by a depending flange 7. The hood further embodies parallel end walls 8 of triangular formation as shown in Figure 3 and a top wall 9 rising upwardly from the rear edge of the bottom wall with the front side of the hood open as indicated at 10.

85

The hood is adapted for mounting upon a collar 11 and the bottom wall 5 of the hood extends rearwardly of the collar 11 as at 12 and the rear extension has an elongated slotted opening 13 provided therein that extends the full width of the bottom wall.

90

As previously stated, the hood may be directly mounted upon the outlet flue of a gas stove or range, but when combined with the collar 11, the latter is mounted upon the out-

95

100

let flue. The products of combustion escaping through the flue enter the hood and contacting the forwardly and upwardly inclined top wall 9 are deflected forwardly of the hood 5 through the unobstructed front opening 10 to be directed away from the walls of the room. Air enters the hood through the slotted opening 13 and by this action increases the velocity of the products of combustion flowing through the hood to discharge them with greater force away from the walls of the room.

As shown in Figures 4 and 5, the forward edges of the side wall 8 are outwardly flanged 15 as at 8a with which the rolled side edges of a grille 14 are engaged, the deflector being used either with, or without the grille. It has also been described that the slotted opening 13 is in the rear extension 12 of the bottom wall 5, 20 but it is to be understood to be within the realm of this invention to locate the opening 13 elsewhere, such as forwardly of the opening 6, to the sides thereof, or in the side walls 8, and in fact be located wherever it will 25 function for increasing draft through the deflector. As shown in Figures 6 to 8, the collar 11 is illustrated as mounted upon the flange 15 that surrounds the outlet flue of the gas range 16 and the bottom wall 5 of the 30 hood is provided with an opening 13a at each side of the opening 6 in the bottom wall of the hood that receives the collar 11. The openings 13a are positioned at opposite sides or laterally of the opening 6 and are disposed 35 rearwardly of the forward edge of the opening 6 as clearly shown in Figure 8, the elongated slotted opening 13 illustrated in Figures 1 to 4 being eliminated in this construction, the laterally positioned opening 13a operating to increase draft through the deflector hood, the latter otherwise being of the 40 same construction as shown in Figures 1 to 3.

From the above detailed description of the invention it is believed that the construction 45 and operation thereof will at once be apparent and while there is herein shown and described the preferred embodiment of the invention, it is nevertheless to be understood that minor changes may be made therein without departing 50 from the spirit and scope of the invention as claimed.

I claim:

1. In a flue cap and deflector, a collar adapted for mounting on the outlet flue of 55 a gas range, a deflector hood having a forward side opening therein parallel with the forward side of the outlet flue, said hood being mounted on the upper end of the collar and said hood having an air inlet opening 60 in the bottom thereof entirely rearwardly of the forward side of the collar.

2. In a flue cap and deflector, a collar adapted for mounting on the outlet flue of a 65 gas range, a deflector hood having a vertical forward side opening therein and mounted

on the upper end of the collar, and said hood having air inlet openings in the bottom thereof in vertical planes laterally and rearwardly of the forward side of the collar.

3. In a flue cap and deflector, a hood having a forward side opening therein and adapted to be placed in communication with the outlet flue of a gas range and another opening therein laterally and entirely rearwardly of the forward edge of the flue opening for ingress of air to increase velocity of flow through the hood.

4. In a flue cap and deflector, a hood having a forward side opening therein and adapted to be placed in communication with the outlet flue of a gas range and having an opening in its bottom laterally and entirely rearwardly of the forward edge of the outlet flue for ingress of air to the hood to increase the velocity of flow through the hood.

5. In a flue cap and deflector, a hood having a top deflector wall and a forward side opening, and a bottom wall, the bottom wall having an opening therein to be placed in communication with the outlet flue of a gas range and said bottom wall having another opening therein located in the bottom wall rearwardly of the forward edge of the first named opening.

6. In a flue cap and deflector, a hood having a top deflector wall and a forward side opening, and a bottom wall, the bottom wall having an opening therein to be placed in communication with the outlet flue of a gas range and said bottom wall having another opening therein for ingress of air to increase velocity of flow through the hood, said last named opening being located in the bottom wall adjacent one wall of the hood and rearwardly of the forward edge of the flue opening.

7. In a flue cap and deflector, a hood having a forward side opening therein and adapted to be placed in communication with the outlet flue of a gas range with said opening in a vertical plane parallel with the vertical side of the outlet flue and said hood having air inlet openings in the bottom laterally and rearwardly of the forward edge of the outlet flue.

8. In a flue cap and deflector, a collar adapted for mounting on the outlet flue of a gas range, a deflector hood having a forward side opening therein in a plane parallel with the forward side of the outlet flue, said hood being mounted on the upper end of the collar, and said hood having air inlet openings in the bottom thereof laterally and rearwardly of the forward side of the collar.

9. In a flue cap and deflector, a deflector hood having a forward side opening therein and adapted for mounting on the outlet flue of a gas range, and means formed within a part of the hood and located rearwardly of the forward edge of the outlet flue for in-

creasing the draft through the hood when in service.

10. In a flue cap and deflector, a hood having a forward side opening therein and 5 adapted to be placed in communication with the outlet flue of a gas range with said opening in a substantially vertical plane parallel with the vertical side of the outlet flue and said hood having openings in the bottom 10 laterally and rearwardly of the forward edge of the outlet flue.

In testimony whereof I affix my signature.
JOSEPH A. McCARTHY.
